ABSTRACT OF THE DISCLOSURE

The present invention distinguishes valid targets from invalid targets in a stacked beam radar surveillance system due to specific signals on one beam, two adjacent beams, or three adjacent beams. During each range bin interval, data words are circulated through the data processor, which words contain the weight of particular range bins on specific beams and are increased by two increments for a hit and decreased by one increment for a miss. When the data words of single or adjacent beams reach predetermined values, a valid target is indicated on a specific beam.

This invention relates to data processing apparatus for processing data input signals in the form of digital pulses and more particularly to a data processing system which is capable of distinguishing data in a first condition from data in a second condition.

The present invention is especially useful, as an example, with radar surveillance systems or the like. Radar systems of this nature receive video return signals in response to exploratory pulses. Upon receipt thereof the video signals are first quantized or digitized with comparison methods to a clock signal initiated after each exploratory pulse, i.e., the undeveloped video signals are converted to a series of ones and zeroes by a video quantizer depending on whether the video return exceeds or does not exceed a threshold level respectively. A video return which exceeds the threshold level of the video quantizer is referred to as a "hit." A video signal that does not exceed the threshold level is referred to as a "miss." A need has developed for an automatic detection system for the automatic processing of the video return from a surveillance radar for determining a ratio of hits and misses which may constitute a valid target or an invalid target.

In automatic processing system now in existence, valid targets are usually generated by exceeding the aforesaid threshold count of quantized (digitized) video hits. This is usually determined by a sequential observer type counter or "sliding window" type threshold count detector. These devices indicate the valid radar target return when the number of digital video hits exceed the threshold count value within a particular range increment (range bin). However, whether returns, radar interference and jamming, etc., which amount to noise on the receiver may produce sufficient hits in a range bin to indicate a valid target return. In some systems all target reports are stored in a computer memory and processed by the computer to distinguish between valid and invalid target reports.

Video signal returns from a single scan beam received by a radar receiver may have a plurality of signals which exceed the threshold level because of the aforesaid reasons. In these cases not all, if any, of these returns can be classified as a target. In figuring on a probability scale, it has been determined that a hit would allow a counter to count up N bits, say for example two increments, and

2

count down $N/2$ bits or one increment for a miss. The probability of a false alarm rate is calculated on an individual hit basis. It has been found by calculations that should the counter, counting its hits and misses is an individual range bin, reach a count of thirteen, there is a probability of 1.7×10^{-6} that the count is a false alarm. Therefore, it is considered that when a count of thirteen has been attained the probabilities of it being a valid target are very high.

10 Prior art systems employ techniques of assuming that N out of M hits indicate a valid target require, for example, majority logic which is enabled on N out of M the data processing machines used therewith will indicate that a target has been registered. Typical majority logic is enabled if 8 video returns, out of 11 indicate a hit, a target is indicated. Too, once the majority logic has been enabled it will continue to register a target until appropriate minority logic is enabled, for example, the video returns fall below 5 hits out of the aforesaid 11.

20 These prior art processing system require that when a stacked beam radar system is used, all of the video inputs are summed in the video quantizer as they are received from the radar receiver. All of the noise of each receiver is also summed and a collapsing loss occurs and consequently the range of the machine itself is greatly reduced.

25 In one particular concept of this invention a plurality of stacked beams from a radar surveillance system is processed detecting a target due to specified signals on one beam, on two adjacent beams, or three adjacent beams. This takes into consideration the hits-per-return ratio of either a single beam or single beam pulse one or both adjacent beams.

30 At each range bin interval which corresponds to the radar pulse width, a four-bit word will be read out of and written back into an associated memory. This four-bit word may be contained in a reversible binary counter which counts up two increments for a hit or a binary one applied thereto and counts down one increment for a miss and is designated as a binary zero. The total count possible in the four-bit word is 16. In one embodiment of this invention a counter is provided for each radar beam and each counter processes a single range bin in a sequential order. After a range bin has been processed its condition found on a single sample is combined with the data of its particular condition previously stored in its address and then returned to memory at its particular location.

35 One object of this invention is to provide a novel and improved data processor which automatically processes digital input data on a real time basis.

40 Another object of this invention is to provide a novel and improved data processor useful for determining valid targets from invalid targets in response to radar video pulses.

45 Another object of this invention is to provide a novel and improved data processor which implements and computes a specified event by application of a pulse to pulse correlation process.

50 These and other objects, features and advantages will become apparent to those skilled in the art when referring to the following detailed description of one preferred embodiment and referenced to the following figures illustrating preferred embodiments of this invention wherein:

55 FIGURE 1 is a simplified block diagram illustrating a preferred embodiment of this invention when used for processing radar video returns;

60 FIGURE 2 is a logic diagram illustrating a read register and the logic gates used therewith;

FIGURES 3A, 3B, 3C, and 3D illustrate a reversible counter used with this invention and its associated enabling logic inputs;

FIGURE 4 is a schematic logic diagram illustrating the threshold detection logic;

FIGURES 5A through 5G are logic diagrams illustrating single beam detection logic;

FIGURE 6 is a logic diagram illustrating two-beam detection logic; and

FIGURES 7A through 7E are logic diagrams illustrating three-beam detection logic.

In determining the hits-per-return ratio of a single range bin the scan-to-scan correlation or the Markov process of probabilities is applied. This process is best explained in the publication entitled "Introduction to Radar Systems" by Merrill I. Skolnick, published by McGraw-Hill, 1962, p. 55.

The actual count procedure followed in this embodiment follows the above process and allows a hit to cause a binary counter to be advanced two counts while a miss causes the counter to count down one count. A false alarm rate can thus be generated using this procedure.

The noise false alarm rate on an individual hit basis was selected. The probability of an incoming video signal being a hit being 0.1 or 10% and the probability of it being a miss being 0.9 or 90%. With this criteria and assuming the counter was in a state X then there is a probability of 0.1 to advance to (X+2) and a probability of 0.9 to decrease to (X-1) the next count signal. The following table may be used as an explanation of the above situation:

TABLE I

Initial State of Counter	Next State of the Counter													
	0	1	2	3	4	5	6	7	8	9	10	11	12	13
0	.9	0	.1	0	0	0	0	0	0	0	0	0	0	0
1	.9	0	0	.1	0	0	0	0	0	0	0	0	0	0
2	0	.9	0	0	.1	0	0	0	0	0	0	0	0	0
3	0	0	.9	0	0	.1	0	0	0	0	0	0	0	0
4	0	0	0	.9	0	0	.1	0	0	0	0	0	0	0
5	0	0	0	0	.9	0	0	.1	0	0	0	0	0	0
6	0	0	0	0	0	.9	0	0	.1	0	0	0	0	0
7	0	0	0	0	0	0	.9	0	0	.1	0	0	0	0
8	0	0	0	0	0	0	0	.9	0	0	.1	0	0	0
9	0	0	0	0	0	0	0	0	.9	0	0	.1	0	0
10	0	0	0	0	0	0	0	0	0	.9	0	0	.1	0
11	0	0	0	0	0	0	0	0	0	0	.9	0	0	.1
12	0	0	0	0	0	0	0	0	0	0	0	.9	0	.1
13	1	0	0	0	0	0	0	0	0	0	0	0	0	0

Table I, but because entries within this column are equal or each row is identical, the probabilities of the count being a false alarm is computed as follows in Table II:

TABLE II

Count:	Probability
0	7.78×10^{-1}
1	8.64×10^{-2}
2	9.60×10^{-2}
3	2.027×10^{-2}
4	1.29×10^{-2}
5	3.69×10^{-3}
6	1.84×10^{-3}
7	6.12×10^{-4}
8	2.71×10^{-4}
9	9.63×10^{-5}
10	3.89×10^{-5}
11	1.31×10^{-5}
12	3.89×10^{-6}
13	1.7×10^{-6}

Turning now to a detailed description of one preferred embodiment of this invention, there is shown in FIGURE 1 a plurality of radar receivers 10 which receive input data from a plurality of input channels which may be quantized video signals from a radar system (not shown). Each video signal is quantized within radar receivers and quantizers 10 and presents digital data on a plurality of output channels designated E₁ through E₇ corresponding to each individual receiver. Seven radar video return beams have been shown here only as an example and it must be understood that more beams may be processed

Each row of the table indicates the initial state of the counter. The counter can only advance to its next state with the probability indicated. For example, with the initial count of three maintained in the counter, it can advance to a five with the probability of 0.1 or it can decrease to 2 with the probability of 0.9 and it has a probability of 0 going to any other state. Since each of the rows in the table sum to 1, it can be treated as a probability matrix A. The usefulness of the matrix is indicated in the following example. If a new matrix B is desired which represents the initial state vs. the state two counts later instead of one count later, the following formula is used:

$$B = A^2$$

To compute the new matrix if C represents the state of the counter N states later then

$$C = A^N$$

When N becomes large enough it has been found that

$$A^N = A^{N+K}$$

where K is any positive integer. This final matrix was called the stable value of the matrix. In this particular matrix the entries in each column are equal to each other, and the sum of the entries in each row are equal to 1.

The above indicates that regardless of the state which the counter started, the probability of it being at a count of three for instance is given by an entry in col. 3 of

by this invention using increased equipment for each beam.

Each receiver 10 receives a video signal from stacked radar beams in real time and in this particular embodiment seven receivers are used for seven particular beams. The E₁-E₇ outputs of these receivers and quantizers 10 are presented to the reversible counters and logic 14.

The read register 12 comprises a plurality of flip-flops F₁ through F₇ which contains the logic for indicating that if true a target has been determined and is triggered by incoming G terms later to be explained. Read register 12 is coupled to data channels of a data storage device such as a core memory device 17 which store data in address locations corresponding to the range bin of the video returns. The data is continually recirculated from the memory 17 through the read register 12 through logic to be explained, updated by the incoming E₁-E₇ terms and stored back into the memory 17 through write register 15 until a target has been ascertained. Read register 12 provides a plurality of outputs F₁-F₇ and each of these outputs is presented to the reversible counters and logic or counter logic 14 through output channels generally designated F. Although not shown in FIG. 1 but which will be described later, each of the outputs F₁-F₇ are also presented to the three beam detection logic 18, the two beam detection logic 20, and the single beam detection logic 21. As will become apparent an F term indicates a target has been determined and an $\bar{F}$ indicates

a target has not been determined. The counter logic 14 comprises a plurality of counters one through seven which corresponds to the terms F_1 – F_7 and also responds to the video signals E emanating from the beam receivers and quantizers 10. The output signals from each counter are generally designated A, B, C and D. Where A is the most significant digit of the read register 12, B is the third least significant digit of the read register 12. C is the second least significant digit of read register 12 and D is the least significant digit of read register 12. When taking all digit terms into consideration, they are indicative of some binary number indicative of the value of the range bins during any specific sample time. Each of these counters operate by their logic, as will be explained later, to cause their associated counters to update the value of the data in a corresponding memory channel by causing the contents thereof to count up two increments for each binary one and count down one increment for each binary zero of the video signals E. The output of the counter logic 14 is coupled to threshold detection gates and logic or threshold detection logic 16 by the lead line generally designated A, B, C, D. The threshold detection logic 16 comprises a plurality of gates G_1 – G_7 and each gate is enabled when a target is indicated by the count contained in the associated counters 14 and as updated by incoming E terms. The output of the G_1 through G_7 gates is presented directly as enabling terms to the write register 15.

Also coupled as inputs to threshold detection logic 16 are the outputs W_2 through W_6 from a three-beam detection logic 18 by the lead line generally designated W. The three-beam detection logic 18 is enabled by the output terms A, B, C, D from memory 17 which indicates the state of the data at corresponding range bins, the F terms (see FIGS. 7A–7E) from read register 12, and also by the video signals E. Also coupled as enabling inputs to threshold detection gates and logic 16 are the outputs X_{1-2} , X_{2-3} , X_{3-4} , X_{4-5} , X_{5-6} , and X_{6-7} from two-beam detection logic (X) 20 which is also enabled by the data stored in memory 17 during specific range bins, the F terms (see FIG. 6) from read register 12, and by the video input signals E. And finally, single beam detection logic 21, which is enabled by the data stored in memory 17 during specific range bins, the F terms (see FIGS. 5A–5G) from read register 12, and the video input signals E, provides enabling signals Z_1 through Z_7 to the threshold logic 16 for determining whether a target has been declared on a single beam. The single beam detection logic 21 is enabled by the video input signals E.

In operation the video signals are presented to counters and logic 14. Each counter as previously indicated will cause the contents of the data being recirculated during a specific corresponding range bin address to increase in value two increments if a hit or a one is determined, but will cause the contents thereof to decrease in value one increment if a miss or a zero has been determined. When the data in the memory 17 during a specific input addressed range bin reaches a count of 13, in the counter and logic 14 by updating signals from receivers 10, it has been determined by the aforementioned probability table that a target has been indicated and the appropriate gate G will be enabled by the threshold detection logic 16. This gate G then will cause the appropriate flip-flop of write register 15 to be enabled and store a target in the memory while resetting the counter to zero.

Further, if two adjacent counters each reach a count of six or more the probability of a hit is also indicated and the appropriate logic gate G will be enabled and this is carried out by two-beam detection logic (X) 20. If three counters indicate that a center counter has a count of eight contained therein and adjacent counters on either side thereof have a count of three or more the probability of a hit is determined and the appropriate threshold gate will register a hit to the write register 15 which will be stored in memory 17.

When the contents of a single storage address in memory 17 stores a target an F is stored and the associated counter is reset to zero. The leading edge of the target is now declared. The next step is to detect when the target has diminished or the trailing edge has been declared. This is accomplished in the same manner with the exception that the counter logic 14 increase the contents (now set to zero by a G_1) to increase two increments on a miss or a zero and decrease one increment on a hit or one from the radar receiver and quantizer 10.

The reversible counter logic 14 comprising binary counters 1 through 7 and each counter has associated therewith an action bit in the form of a plurality of flip-flops F_1 through F_7 as shown in FIGURE 2. These flip-flops are of the set-reset type and wherein flip-flop 24 is enabled by the following logic equation as stated in Boolean notations:

$$\text{Set } F_1 = (G_1 \bar{F}_1 + \bar{G}_1 F_1) \bar{K}$$

$$\text{Reset } F_1 = \overline{\text{Set } F_1}$$

Flip-flop 26 is set and reset by the following:

$$\text{Set } F_2 = (G_2 \bar{F}_2 + \bar{G}_2 F_2) \bar{K}$$

$$\text{Reset } F_2 = \overline{\text{Set } F_2}$$

Flip-flop 28 is set and reset by the following:

$$\text{Set } F_3 = (G_3 \bar{F}_3 + \bar{G}_3 F_3) \bar{K}$$

$$\text{Reset } F_3 = \overline{\text{Set } F_3}$$

Flip-flop 30 is set and reset by the following:

$$\text{Set } F_4 = (G_4 \bar{F}_4 + \bar{G}_4 F_4) \bar{K}$$

$$\text{Reset } F_4 = \overline{\text{Set } F_4}$$

Flip-flop 32 is set and reset by the following:

$$\text{Set } F_5 = (G_5 \bar{F}_5 + \bar{G}_5 F_5) \bar{K}$$

$$\text{Reset } F_5 = \overline{\text{Set } F_5}$$

Flip-flop 34 is set and reset by the following:

$$\text{Set } F_6 = (G_6 \bar{F}_6 + \bar{G}_6 F_6) \bar{K}$$

$$\text{Reset } F_6 = \overline{\text{Set } F_6}$$

Flip-flop 36 is set and reset by the following:

$$\text{Set } F_7 = (G_7 \bar{F}_7 + \bar{G}_7 F_7) \bar{K}$$

$$\text{Reset } F_7 = \overline{\text{Set } F_7}$$

Where F terms are read from memory 17 indicating a valid target F or invalid target $\bar{F}$ has been previously stored and G is an enabling term from the threshold logic 16 indicating a G as a target has been declared by the previous detection signals W, X or Z and will be stored as F while $\bar{G}$ indicates no target declared and is stored as $\bar{F}$.

FIGURE 2 shows a schematic diagram for implementing the above equations wherein the set input of a flip-flop 26 is coupled to an AND gate 40 which is enabled by a $\bar{K}$, a clear and reset memory position button (not shown). AND gate 40 is also enabled by the output of OR gate 42. OR gate 42 is enabled by the output of a pair of AND gates 44 and 46. AND gate 44 being enabled by a G_1 from threshold detection logic 16 and a $\bar{F}_1$, $\bar{F}_1$ term indicating that the $\bar{F}_1$ action bit flip-flop is false, and that a target has not been previously declared and a G_1 indicating that a target has been declared during this E beam sweep. AND gate 46 is enabled by a $\bar{G}_1$ and a F_1 , indicating that a target has already been stored, thus resetting counter 14 to zero as will be explained. The output of AND gate 40 is presented to an inverter 48 which is presented to the reset input of flip-flop 44.

Flip-flop 26 is set by the output of AND gate 50 which in turn is enabled by a $\bar{K}$ and the output of OR gate 52. OR gate 52 is enabled by the outputs from a pair of AND gates 54 and 56. AND gate 54 is enabled by G_2 and a $\bar{F}_2$. AND gate 56 is enabled by a $\bar{G}_2$ and a F_2 . The output of AND gate 50 is also coupled to the input of an inverter

58, the output therefrom being coupled to the reset input of flip-flop 26.

Flip-flop 28 is set by the output of AND gate 60 which in turn is enabled by $\bar{K}$ and the output of OR gate 62. OR gate 62 is enabled by the outputs from a pair of AND gates 64 and 66. AND gate 64 is enabled by G_3 and $\bar{F}_3$. AND gate 66 is enabled by a $\bar{G}_3$ and F_3 . The output of AND gate 60 is also coupled to an input of an inverter 68 and the output therefrom being coupled to the reset input of flip-flop 28.

Flip-flop 30 is set by the output of AND gate 70 which, in turn, is enabled by $\bar{K}$ and the output of OR gate 72. OR gate 72 is enabled by the outputs from a pair of AND gates 74 and 76. AND gate 74 is enabled by a G_4 and a $\bar{F}_4$. AND gate 76 is enabled by a $\bar{G}_4$ and a F_4 . The output of AND gate 70 is coupled to the input of an inverter 78 and the output therefrom being coupled to the reset input of flip-flop 30.

Flip-flop 32 is set by the output of AND gate 80 which in turn is enabled by $\bar{K}$ and the output from OR gate 82. OR gate 82 is enabled by the outputs of a pair of AND gates 84 and 86. AND gate 84 is enabled by a G_5 and a $\bar{F}_5$. AND gate 86 is enabled by a $\bar{G}_5$ and a F_5 . The output of AND gate 80 is also coupled to the input of an inverter 88 the output therefrom being coupled to the reset input of flip-flop 32.

Flip-flop 34 is set by the output of AND gate 90 which, in turn, is enabled by a $\bar{K}$ and the output of OR gate 92. OR gate 92 is enabled by the outputs from a pair of AND gates 94 and 96. AND gate 94 is enabled by a G_6 and a $\bar{F}_6$. AND gate 96 is enabled by a $\bar{G}_6$ and a F_6 . The output of AND gate 90 is also coupled to the input of an inverter 98, the output therefrom being coupled to the reset input of flip-flop 34.

Finally, flip-flop 36 is set by the output of OR gate 100, which, in turn, is enabled by a $\bar{K}$ and the output of AND gate 102. OR gate 102 is enabled by the outputs from a pair of AND gates 104 and 106. AND gate 104 is enabled by a G_7 and a $\bar{F}_7$. AND gate 106 is enabled by a $\bar{G}_7$ and a F_7 . The output of AND gate 100 is also coupled to the input of an inverter 108, the output therefrom being coupled to the reset input of flip-flop 36.

In the processing of the incoming video returns during an individual range bin a reversible binary counting means 14 in the form of a plurality of four-bit binary counters is provided for each incoming E beam. Each counter comprises four flip-flops A through D, each of which provides a 16-bit binary count. FIGURES 3A through 3D illustrate only one counter and its associated logic and it is to be understood that a counter must be provided for each radar beam substantially as this one shown and described. The contents of a specific address location of memory 17 is loaded into the counters 14 and is then updated by incoming hits or misses from the radar receiver 10 in the form of E terms.

Each flip-flop in the counter is set and reset by reversible counting logic as shown in FIGURES 3A through 3D. Flip-flop 110 as shown in FIGURE 3A is set and reset by the following Boolean equation:

$$\begin{aligned} \text{Set } A_1 = & E_1 \bar{F}_1 \bar{G}_1 \bar{K} (A_1 + B_1 C_1) + A_1 \bar{E}_1 \bar{F}_1 \bar{G}_1 (B_1 + C_1 + D_1) \\ & + \bar{E}_1 F_1 \bar{G}_1 \bar{K} (A_1 + B_1 C_1) + A_1 E_1 F_1 \bar{G}_1 \bar{K} (B_1 + C_1 + D_1) \\ \text{Reset } A_1 = & \text{Set } \bar{A}_1 \end{aligned}$$

FIGURE 3A illustrates a logic block diagram for the implementation of the above equation wherein the set input of flip-flop 110 is enabled by the output of OR gate 112. OR gate 112 in turn is enabled by the outputs of AND gates 114, 116, 118 or 120. AND gate 114 is enabled by $\bar{K}$, an incoming video term E_1 , the term $\bar{F}_1$ from read register 12, a $\bar{G}_1$ term indicating that a hit has not been detected by the threshold detection logic 16. AND gate 114 is also enabled by the output from OR gate 122. OR gate 122 is enabled by data read directly from the memory 17. An OR gate 122 is enabled by

the term A_1 , which indicates that a count of 8 or more is contained in the memory or by the output from AND gate 124 which indicates that the word in the memory location is either 6 or 7 because these terms will have a B_1 true and a C_1 true. Thus, if the A_1 is 8 or more the MSD flip-flop 110 will be enabled or if the $\bar{G}_1$ is present indicating that a target has not been determined and an incoming video E_1 is present and a 6, 7 or 8 is present the flip-flop 110 is enabled. This is because if a 2 is added to 6 it becomes 8 and therefore the MSD A_1 should be true. The same is true for 7 and 8 which become 9 or 10 by virtue of the E_1 .

AND gate 118 is enabled by the terms $\bar{E}_1$, F_1 , $\bar{G}_1$, $\bar{K}$ and the output of OR gate 132. OR gate 132 is enabled by the term A_1 which indicates that the contents of that particular memory location is 8 or above. OR gate 132 is also enabled by the output of AND gate 134 which is enabled by the terms B_1 , C_1 which is 6 or 7 and therefore an incoming video E_1 will enable flip-flop 110.

Next it becomes necessary to cause the logic to declare a trailing edge or that the target has decreased. This is accomplished, as mentioned, by causing the contents of the memory at a particular addressed bin location to increase two increments on incoming $\bar{E}_1$ in the presence of an F_1 and to decrease one increment by an E_1 in the presence of an F_1 . Note that the equations are identical as inputs to AND gates 118 and 120 when compared to the inputs to AND gates 114 and 116 respectively with the exception of the E and F terms.

AND gate 116 is enabled by an $\bar{F}_1$, an $\bar{F}_1$ indicating that the read register 12 does not indicate a target stored and the radar receiver 10 detects a miss, an $\bar{G}_1$ indicating a threshold has not been detected, the output of OR gate 128, a $\bar{K}$, and an A_1 from the memory 17. Therefore the object is to cause the counter to count up 2 increments on $\bar{E}_1$ and down 1 increment on E_1 . AND gate 128 is enabled by a C_1 , a D_1 or a B_1 which indicate that A_1 must be true when a 1 count is added to increments in which C_1 , D_1 or B_1 is true as well as if an A_1 applied to AND gate 116 indicates that the state of the word stored in that particular memory location is 8 or more.

AND gate 120 is enabled by the terms E_1 , F_1 , $\bar{G}_1$, $\bar{K}$, A_1 and the output from OR gate 138 which, in turn, is enabled by the terms C_1 , D_1 or B_1 .

The output of OR gate 112 is also applied to an inverter 140 the output of which is applied to the reset input of flip-flop 110.

The B_1 flip-flop 142 is enabled by the following equation:

$$\begin{aligned} \text{Set } B_1 = & E_1 \bar{F}_1 \bar{G}_1 (\bar{A}_1 \bar{B}_1 C_1 + \bar{A}_1 B_1 \bar{C}_1 + A_1 \bar{B}_1 C_1 \bar{D}_1) \bar{K} \\ & + \bar{E}_1 \bar{F}_1 \bar{G}_1 [A_1 \bar{B}_1 \bar{C}_1 \bar{D}_1 + \bar{A}_1 B_1 (C_1 + D_1)] \bar{K} \\ & + \bar{E}_1 F_1 \bar{G}_1 (\bar{A}_1 \bar{B}_1 C_1 + \bar{A}_1 B_1 \bar{C}_1 + A_1 \bar{B}_1 C_1 \bar{D}_1) \bar{K} \\ & + E_1 F_1 \bar{G}_1 [A_1 \bar{B}_1 \bar{C}_1 \bar{D}_1 + \bar{A}_1 B_1 (C_1 + D_1)] \bar{K} \end{aligned}$$

$$\text{Reset } B_1 = \text{Set } \bar{B}_1$$

FIGURE 3B illustrates a logic block diagram for implementing the above equation wherein the set input of flip-flop 142 is enabled by the output of OR gate 144. OR gate 144 in turn is enabled by the output of AND gates 146, 148, 150 and 152. AND gate 146 is enabled by the incoming video return E_1 , the $\bar{F}_1$, indicating no target stored, from read register 12, a $\bar{G}_1$ term indicating the threshold had not been detected in this range bin, at a particular address, by the threshold detection logic 16 and a $\bar{K}$. Also providing an enabling term to AND gate 146 is the output from OR gate 154. OR gate 154 is enabled by the output of AND gate 156, 158 or 160 wherein these AND gates are enabled by the outputs of memory 17 indicating the present state of the range bin before the incoming video returns enabling AND gate 146, wherein AND gate 156 is enabled when $\bar{A}_1$, $\bar{B}_1$ and C_1 is stored in the memory 17. This indicates that a 2 or 3 is presently stored in the memory and that they

will be increased to 4 or 5 by an incoming E_1 . Flip-flop 142 must be set true because the numbers 6 or 7 must have a B true when expressed in binary terms. AND gate 158 is enabled by the terms $\bar{A}_1$, B_1 and $\bar{C}_1$ which indicates that a 4 or 5 is presently stored in the memory and that they will be increased to 6 or 7 by an incoming E_1 , and set flip-flop 142. Finally, the last enabling term to OR gate 154 comes from the AND gate 160 which is enabled by A_1 , $\bar{B}_1$, C_1 and D_1 which indicates that the number presently stored in memory 17 is 10 and the same rules apply.

AND gate 148 is enabled by an $\bar{E}_1$, a $\bar{F}_1$, a $\bar{G}_1$ and a $\bar{K}$. It is also enabled by the output from OR gate 162. OR gate 162 is in turn enabled by the outputs of AND gate 164 or AND gate 168. AND gate 164 is enabled by the term A_1 , $\bar{B}_1$, $\bar{C}_1$, $\bar{D}_1$. This indicates that the 8 is stored in the memory for the particular range bin operated on and that should an $\bar{E}_1$ be applied the value must decrease 1 count to 7 in which B must be true. AND gate 168 is enabled by the output $\bar{A}_1$, B_1 and the output from OR gate 170 which is in turn enabled by the terms C_1 , D_1 which indicates that the numbers 5, 6 or 7 is presently stored in the memory at that particular bin location.

AND gate 150 is enabled by the terms $\bar{E}_1$, F_1 , $\bar{G}_1$, $\bar{K}$ and the output from OR gate 172. OR gate 172 is enabled by the output of AND gate 174, 176 or 178, wherein AND gate 174 is enabled by the term $\bar{A}_1$, $\bar{B}_1$, C_1 which indicates a No. 2 or 3 is stored. The output of AND gate 176 is enabled by an $\bar{A}_1$, a B_1 , a $\bar{C}_1$ which indicates that the No. 4, 5 is stored in the memory and finally the output of AND gate 178 is enabled by the terms A_1 , $\bar{B}_1$, C_1 , and D_1 indicating that the No. 10 is stored.

AND gate 152 is enabled by the terms E_1 , F_1 , $\bar{G}_1$, $\bar{K}$ and the output from OR gate 180. OR gate 180 is enabled by the outputs of AND gates 182, 184. AND gate 182 is enabled by the terms A_1 , $\bar{B}_1$, C_1 and $\bar{D}_1$ which indicates that a No. 8 is stored. AND gate 184 is enabled by the terms $\bar{A}_1$, B_1 and the output from OR gate 186. OR gate 186 is enabled by the term C_1 or D_1 which indicates that AND gate 184 is enabled if any of the terms 5, 6 or 7 is stored in the memory.

The output of OR gate 144 is also applied to the input of an inverter 187 the output of which is applied as the reset input to flip-flop 142.

The C_1 flip-flop 188 is set and reset by the following equations:

$$\begin{aligned} \text{Set } C_1 = & E_1 \bar{F}_1 \bar{G}_1 (\bar{A}_1 \bar{B}_1 \bar{C}_1 + \bar{A}_1 B_1 \bar{C}_1 + A_1 \bar{B}_1 \bar{C}_1) \bar{K} \\ & + E_1 \bar{F}_1 \bar{G}_1 (\bar{A}_1 C_1 D_1 + B_1 \bar{C}_1 \bar{D}_1 + A_1 \bar{C}_1 \bar{D}_1 + \bar{B}_1 C_1 D_1) \bar{K} \\ & + E_1 F_1 \bar{G}_1 (\bar{A}_1 \bar{B}_1 \bar{C}_1 + \bar{A}_1 B_1 \bar{C}_1 + A_1 \bar{B}_1 \bar{C}_1) \bar{K} \\ & + E_1 F_1 \bar{G}_1 (\bar{A}_1 C_1 D_1 + B_1 \bar{C}_1 \bar{D}_1 + A_1 \bar{C}_1 \bar{D}_1 + \bar{B}_1 C_1 D_1) \bar{K} \\ \text{Reset } C_1 = & \bar{S}et \bar{C}_1 \end{aligned}$$

FIGURE 3C illustrates a logic block diagram for the implementation of the above equation wherein the set input of flip-flop 188 is enabled by the output of OR gate 190 which is enabled by the outputs of AND gates 192, 194, 196 or 198. AND gate 192 is enabled by the E_1 term which indicates the incoming video hit is to be recorded, a $\bar{F}_1$ from the read threshold detection logic 16, a $\bar{G}_1$ from the read register 12 indicating that a threshold had not been detected by the state of the previous range bin. $\bar{K}$ indicating that a clear push button had not been enabled and the output from OR gate 200. OR gate 200 is enabled by the output from AND gates 202, 204 or 206 wherein AND gate 202 is enabled by the terms $\bar{A}_1$, $\bar{B}_1$, $\bar{C}_1$ which indicates that a No. 0 or 1 is stored in the memory. AND gate 204 is enabled by $\bar{A}_1$, B_1 or $\bar{C}_1$ indicating that a No. 4, 5 is stored. AND gate 206 is enabled by the term $\bar{A}_1$, $\bar{B}_1$, C_1 indicating that the No. 8 or 9 is stored.

AND gate 194 is enabled by the terms $\bar{E}_1$, $\bar{F}_1$, $\bar{G}_1$, $\bar{K}$ and the output from OR gate 208. OR gate 208 is enabled by the outputs of AND gates 210, 212, 214 or 216. AND

gate 210 is enabled by the terms $\bar{A}_1$, C_1 , D_1 which indicates that the No. 3 or 7 is stored. AND gate 212 is enabled by the terms B_1 , $\bar{C}_1$ and $\bar{D}_1$ indicating that a 4 or 12 is stored. AND gate 214 is enabled by the terms A_1 , $\bar{C}_1$, D_1 indicating that an 8 or 12 is stored. AND gate 216 is enabled by a $\bar{B}_1$, C_1 and D_1 indicating that a 3 is stored.

AND gate 196 is enabled by the terms $\bar{E}_1$, F_1 , $\bar{G}_1$, and $\bar{K}$ and the output from OR gate 218. OR gate 218 is enabled by the outputs of an AND gates 220, 222 and 224. The AND gate 220 is enabled by the terms $\bar{A}_1$, $\bar{B}_1$, and $\bar{C}_1$ indicating that 1 or 0 is stored. AND gate 222 is enabled by the terms $\bar{A}_1$, B_1 and $\bar{C}_1$, indicating that a 4 or 5 is stored. AND gate 224 is enabled by A_1 , $\bar{B}_1$, $\bar{C}_1$ indicating that an 8 or 9 is stored.

AND gate 198 is enabled by an $\bar{E}_1$, $\bar{F}_1$, $\bar{G}_1$, $\bar{K}$ and the output from OR gate 226. OR gate 226 is enabled by the output of AND gates 228, 230, 232 or 234. AND gate 228 is enabled by an $\bar{A}_1$, a C_1 , D_1 indicating that a 3 or 7 is stored. AND gate 230 is enabled by a B_1 , a $\bar{C}_1$, $\bar{D}_1$ indicating that a 4 or 12 is stored. AND gate 232 is enabled by an A_1 , $\bar{C}_1$ and a $\bar{D}_1$ indicating that an 8 or 12 is stored. AND gate 234 is enabled by a $\bar{B}_1$, C_1 and D_1 indicating that a 3 or 11 is stored.

The output of OR gate 190 is also applied to an inverter 235, the output of which provides the reset input to flip-flop 188.

Referring now to FIGURE 3D, a flip-flop 236 which is set and reset by the following equation:

$$\begin{aligned} \text{Set } D_1 = & E_1 \bar{F}_1 \bar{G}_1 D_1 \bar{K} + E_1 F_1 \bar{G}_1 D_1 \bar{K} \\ & + E_1 F_1 \bar{G}_1 D_1 \bar{K} + E_1 F_1 \bar{G}_1 D_1 \bar{K} \\ \text{Reset } D_1 = & \bar{S}et \bar{D}_1 \end{aligned}$$

The FIGURE 3D illustrates a logic block diagram for implementation of the above equation where the set input of flip-flop 236 is enabled by the output of OR gate 238. OR gate 238 is enabled by the output of AND gates 240, 242, 244 or 246. AND gate 240 is enabled by an $\bar{E}_1$, an $\bar{F}_1$, a $\bar{G}_1$, a D_1 and a $\bar{K}$. The E_1 term indicates that a video return indicates a hit, a $\bar{F}_1$ indicates that the action bit is not enabled, $\bar{G}_1$ indicates that the previous threshold gate has not been enabled, the D_1 indicates that the least significant digit of the previous number stored in the memory is true.

AND gate 242 is enabled by an $\bar{E}_1$, $\bar{F}_1$, $\bar{G}_1$, $\bar{K}$ and a $\bar{D}_1$, the $\bar{D}_1$ indicating that the least significant digit of the previous stored number is false and the $\bar{E}_1$ that the video return represents a miss. AND gate 244 is enabled by an $\bar{E}_1$, an $\bar{F}_1$, a $\bar{G}_1$ and a D_1 , the F_1 indicating that the action bit in the read register 12 corresponding to this particular radar beam has the action bit enabled. AND gate 246 is enabled by an E_1 , an F_1 , a $\bar{D}_1$, a $\bar{K}$ and a $\bar{G}_1$, the G_1 indicating that the corresponding threshold gate previously stored was false. The output of OR gate 238 is also applied to the input of inverter 247 the output of which is applied as the reset signal to flip-flop 236.

In operation of this counter it is necessary for the counter of a specific channel to check the contents of the memory at a specific location and if the incoming signal is an E to increase the count 2 bits and if the incoming signal is an $\bar{E}$ to decrease the count one bit in the presence of an $\bar{F}$ and vice versa in the presence of an F. For example, the number in the memory is a 7 which is expressed in binary numbers as 0111, thus the input signal would be $\bar{A}BCD$. If the incoming signal is E then the counter must advance to 9 which is expressed binarily as 1001 or $ABC\bar{D}$. Thus, the $\bar{A}$ must be changed to A and therefore flip-flop 10 must be true. One can note that AND gate 114 is enabled by E_1 if a B_1 and C_1 is present which it is for the No. 7. The B must change to $\bar{B}$ and the C must change to $\bar{C}$ and the D remains. Thus, it can be noted that flip-flop 142 does not become enabled on any

condition if $\overline{ABCD}$ and an E and $\overline{F}$ is presented to any gate. Note that the reverse happens on $\overline{E}$ and F terms causing the counter 14 to seek a number less than 13 for determining that the target has diminished.

When $\overline{E}$ appears in the presence of $\overline{F}$ the counter 14 decreases one bit. This can be established by referring to the state of the memory 17 at a particular address location and decreasing the count one bit and enabling the appropriate flip-flop to the set or reset conditions.

Threshold detection logic and gates 16 provide enabling outputs G_1 through G_7 when the following equations are satisfied:

$$\begin{aligned} G_1 &= Z_1 + X_{1-2} + W_2 \\ G_2 &= Z_2 + X_{1-2} + X_{2-3} + W_2 + W_3 \\ G_3 &= Z_3 + X_{2-3} + X_{3-4} + W_2 + W_3 + W_4 \\ G_4 &= Z_4 + X_{3-4} + X_{4-5} + W_3 + W_4 + W_5 \\ G_5 &= Z_5 + X_{4-5} + X_{5-6} + W_4 + W_5 + W_6 \\ G_6 &= Z_6 + X_{5-6} + X_{6-7} + W_5 + W_6 \\ G_7 &= Z_7 + X_{6-7} + W_6 \end{aligned}$$

where

$$\begin{aligned} Z_1 &= (E_1\overline{F}_1 + E_1F_1)(A_1B_1 + A_1C_1D_1) \\ Z_2 &= (E_2\overline{F}_2 + E_2F_2)(A_2B_2 + A_2C_2D_2) \\ Z_3 &= (E_3\overline{F}_3 + E_3F_3)(A_3B_3 + A_3C_3D_3) \\ Z_4 &= (E_4\overline{F}_4 + E_4F_4)(A_4B_4 + A_4C_4D_4) \\ Z_5 &= (E_5\overline{F}_5 + E_5F_5)(A_5B_5 + A_5C_5D_5) \\ Z_6 &= (E_6\overline{F}_6 + E_6F_6)(A_6B_6 + A_6C_6D_6) \\ Z_7 &= (E_7\overline{F}_7 + E_7F_7)(A_7B_7 + A_7C_7D_7) \end{aligned}$$

and

$$\begin{aligned} X_{1-2} &= [A_1 + B_1C_1D_1 + B_1(E_1\overline{F}_1 + E_1F_1)] \\ &\quad [A_2 + B_2C_2D_2 + B_2(E_2\overline{F}_2 + E_2F_2)]Z_1Z_2 \\ X_{2-3} &= [A_2 + B_2C_2D_2 + B_2(E_2\overline{F}_2 + E_2F_2)] \\ &\quad [A_3 + B_3C_3D_3 + B_3(E_3\overline{F}_3 + E_3F_3)]Z_2Z_3 \\ X_{3-4} &= [A_3 + B_3C_3D_3 + B_3(E_3\overline{F}_3 + E_3F_3)] \\ &\quad [A_4 + B_4C_4D_4 + B_4(E_4\overline{F}_4 + E_4F_4)]Z_3Z_4 \\ X_{4-5} &= [A_4 + B_4C_4D_4 + B_4(E_4\overline{F}_4 + E_4F_4)] \\ &\quad [A_5 + B_5C_5D_5 + B_5(E_5\overline{F}_5 + E_5F_5)]Z_4Z_5 \\ X_{5-6} &= [A_5 + B_5C_5D_5 + B_5(E_5\overline{F}_5 + E_5F_5)] \\ &\quad [A_6 + B_6C_6D_6 + B_6(E_6\overline{F}_6 + E_6F_6)]Z_5Z_6 \\ X_{6-7} &= [A_6 + B_6C_6D_6 + B_6(E_6\overline{F}_6 + E_6F_6)] \\ &\quad [A_7 + B_7C_7D_7 + B_7(E_7\overline{F}_7 + E_7F_7)]Z_6Z_7 \\ W_2 &= [(F_1\overline{F}_2F_3) + (F_1F_2\overline{F}_3)][(E_2\overline{F}_2 + E_2F_2)(B_2C_2 + A_2) \\ &\quad + A_2(B_2 + C_2 + D_2)][(E_1\overline{F}_1 + E_1F_1)(C_1 + D_1) + \overline{A}_1B_1] \\ &\quad [(E_3\overline{F}_3 + E_3F_3)(C_3 + D_3) + (\overline{A}_3B_3)]\overline{X}_{1-2}X_{2-3} \\ W_3 &= [\overline{F}_2\overline{F}_3F_4] + (F_2F_3\overline{F}_4)][(E_3\overline{F}_3 + E_3F_3)(B_3C_3 + A_3) \\ &\quad + A_3(B_3 + C_3 + D_3)][(E_2\overline{F}_2 + E_2F_2)(C_2 + D_2) + (A_2B_2)] \\ &\quad [(E_4\overline{F}_4 + E_4F_4)(C_4 + D_4) + (\overline{A}_4B_4)]\overline{X}_{2-3}X_{3-4} \\ W_4 &= [\overline{F}_3\overline{F}_4F_5] + (F_3F_4\overline{F}_5)][(E_4\overline{F}_4 + E_4F_4)(B_4C_4 + A_4) \\ &\quad + A_4(B_4 + C_4 + D_4)][(E_3\overline{F}_3 + E_3F_3)(C_3 + D_3) + (\overline{A}_3B_3)] \\ &\quad [(E_5\overline{F}_5 + E_5F_5)(C_5 + D_5) + (\overline{A}_5B_5)]\overline{X}_{3-4}X_{4-5} \\ W_5 &= [\overline{F}_4\overline{F}_5F_6] + (F_4F_5\overline{F}_6)][(E_5\overline{F}_5 + E_5F_5)(B_5C_5 + A_5) \\ &\quad + A_5(B_5 + C_5 + D_5)][(E_4\overline{F}_4 + E_4F_4)(C_4 + D_4) + (\overline{A}_4B_4)] \\ &\quad [(E_6\overline{F}_6 + E_6F_6)(C_6 + D_6) + (\overline{A}_6B_6)]\overline{X}_{4-5}X_{5-6} \\ W_6 &= [\overline{F}_5\overline{F}_6F_7] + (F_5F_6\overline{F}_7)][(E_6\overline{F}_6 + E_6F_6)(B_6C_6 + A_6) \\ &\quad + A_6(B_6 + C_6 + D_6)][(E_5\overline{F}_5 + E_5F_5)(C_5 + D_5) + (\overline{A}_5B_5)] \\ &\quad [(E_7\overline{F}_7 + E_7F_7)(C_7 + D_7) + (\overline{A}_7B_7)]\overline{X}_{5-6}X_{6-7} \end{aligned}$$

The G_1 output from the threshold logic gates 16 is enabled by the terms Z_1 or X_{1-2} or W_2 . The Z_1 term indicates that a single beam detection has been declared on the E_1 output of the radar receiver 10. The X_{1-2} indicates that two beam detection logic 20 has declared a target on the output X_{1-2} and will be explained herein-after. The W_2 indicates three beam detection logic indicating that three adjacent beams have declared a target on the W_2 output of the three beam detection logic 18. This logic is shown in FIGURE 4.

If a threshold gate, either G_1 through G_7 is enabled, it provides an output to the reversible counters and logic 14 for indicating therein that a target has been declared and also provides enabling terms to the write register 15 as shown in FIGURE 1. It provides the G_1 through G_7 terms for enabling the various F_1 through F_7 flip-flops as previously described.

The above logic equation can best be implemented by the following logic block diagram shown in FIGURE 4 wherein the terms G_1 through G_7 emanate from the OR gates 250, 252, 254, 256, 258, 260 and 262 respectively. Or gate 250 is enabled by the terms Z_1 , X_{1-2} , or W_2 . Where Z_1 indicates single beam detection from a single radar beam lobe of the E_1 signal from the radar receiver and quantizer 10, the X_{1-2} being provided from the two beam detection logic 20 indicating that the E_1 and E_2 from the stacked beams received by the receiver and quantizer 10 each contain six bits in adjacent counters within the reversible counter logic 14 as previously described. The W_2 indicates that the center of three adjacent beams have counted 8 in its respective counter and the above and below beam has counted to at least 3, in their respective counters within the reversible counter and logic 14.

OR gate 252 is enabled by Z_2 , X_{1-2} , X_{2-3} , W_2 or a W_3 . Thus, if adjacent outputs X_{1-2} and X_{2-3} are enabled then a G_2 threshold gate is enabled providing the G_2 term. Too, if a W_2 or a W_3 is present simultaneously then the G_2 output is enabled. And finally if a Z_2 is enabled from a single beam detection logic then a G_2 gate is also enabled. The same holds true for the OR gate 254, when enabled by X_{2-3} , an X_{3-4} , a W_2 , a W_3 , a W_4 or a Z_3 . OR gate 256 is enabled by an X_{3-4} , an X_{4-5} , a W_3 , a W_4 , a W_5 or a Z_4 . OR gate 258 is enabled providing a G_5 term when an X_{4-5} , an X_{5-6} , a W_4 , a W_5 , a W_6 or a Z_5 is present. OR gate 260 provides the G_6 term to the write register and is enabled by an X_{5-6} , X_{6-7} , W_5 , W_6 or a Z_6 , and finally OR gate 262 provides a G_7 on its output and is enabled by an X_{6-7} , a W_6 or a Z_7 .

With reference to FIGURES 5A through 5G single beam detection logic enables a Z_1 through Z_7 output if the previously stated equations are true wherein these figures illustrate, by way of an example, that Z_1 is enabled providing a single beam detection logic detection term when an E_1 beam is present from the radar receiver 10 and a $\overline{F}_1$ is present from the read register 12 indicating that no target has yet been stored and the output from the reversible counters 14 indicate that the count now present in the memory 17 is A_1B_1 which indicates that a count of 12 is stored, or an $A_1C_1D_1$ which indicates that a count of 11 is stored. On an incoming E_1 beam the contents of the reversible counter counts up two bits indicating a 13 or a 14 will be stored and the G_1 output from the threshold logic 16 will be enabled. The $E_1\overline{F}_1$ indicates a leading edge of a target is stored when the E_1 beam presents a valid target and an $\overline{F}_1$ indicates no target stored in memory 17, as previously stated. Z_1 is also enabled if an $\overline{E}_1$ and an F_1 is present indicating the target has diminished by the $\overline{E}_1$ which causes the counter to count down one bit and an F_1 indicating that a target has been stored and the counter has been reset and the contents of the counter falls below the 13 initial count the target value. This explanation will hold true for the Z_2 through Z_7 logic and will not be explained herein.

The two beam detection logic (X) 20 as shown in FIGURE 1 provides six outputs which when enabled indicates that adjacent E beams from the radar receiver 10 have counted six or more hits on the adjacent counters therein. For example, if the X_{1-2} is enabled it indicates that the beam E_1 and E_2 from the stacked beams received by the receiver and quantizer 10 have each counted six hits. Likewise, if X_{2-3} is enabled it indicates that E_2 and E_3 have counted six hits during their specific range bin times or address times, and therefore if adja-

cent beams indicate the required six or more count the threshold logic is satisfied and an appropriate G term is generated from the threshold detection logic 16. The X logic as previously stated is best implemented by the logic diagram as shown in FIGURE 6 and when taken in consideration with the previously stated equation an A_1 indicates, for an example, that the number 8 has previously been stored or the $B_1C_1D_1$ indicates that a 7 has previously been stored and therefore the next oncoming hit will increase the numbers to 10 or 9 respectively, or if a 4 or 5 is stored the B_1 is true and when taken in consideration that the next incoming E_1 term will cause the contents of the memory 17 to advance to 6 or 7 because of its increase by 2 increments and at the same time the adjacent beam has a 8 or 7 stored as indicated by the A_2 and the $B_2C_2D_2$ respectively or a 4 or 5 has been stored indicated by the B_2 and an E_2 term is forthcoming the output X_{1-2} will be enabled indicating a target on two beams has been simultaneously generated. This is only true providing that no single beam detection has been found and this is indicated by the term $\bar{Z}_1$ and $\bar{Z}_2$. It should also be noted that an $\bar{E}_1F_1$ or an $\bar{E}_2F_2$ is used to indicate diminishing targets as previously stated. The same holds true for all of the outputs from the two-beam detection logic 20 for indicating targets by reference to adjacent beams.

The three-beam detection logic 18 as shown in FIGURES 7A through 7E provides the output terms W_2 , W_3 , W_4 , W_5 and W_6 . When one of these W terms is enabled by its logic gate it indicates that three adjacent beams from the radar receiver and quantizer 10 have their center beams containing a count of 8 or more and two adjacent beams having a count of 3 or more which is stored in its respective bin address locations within the memory 17. This is realized by the equation as previously stated.

Taking, for example, the W_2 output which is enabled by an $F_1F_2F_3$ which indicates that all the targets in these particular memory locations from the read register 12 are storing a target or, in the alternative, a $\bar{F}_1\bar{F}_2\bar{F}_3$ indicates no target stored. In either case three adjacent targets must show that they all have either stored targets or no stored targets. Also, to enable a W_2 , for example, it is required that an $E_2\bar{F}_2$ or $\bar{E}_2F_2$ be present where an $E_2\bar{F}_2$ indicates incoming hits from the radar receiver 10 indicates a leading edge. While the $\bar{E}_2F_2$ indicates a trailing edge. Thus if the $E_2\bar{F}_2$ or the $\bar{E}_2F_2$ is present the counter shall be incremented to two bits. At this specific location the previous count already stored in the memory 17 is brought into the counter 17 for incrementation by the above E_2F_2 terms, and if, for example, the A_2 is present indicating that the data stored at this particular address location indicates an 8 or above it will advance the counter to a 10 which is sufficient for a center beam count in the three-beam detection logic. The same holds true for an A_2 and a B_2 , or an A_2 and a C_2 , or an A_2 and a D_2 . Also, the logic then looks to the adjacent beams for exact example the one channel from the memory or the three channel from the memory for a count of 3 or more but less than 8, as indicated by the C_1 or D_1 and the $\bar{A}_1B_1$. It should also be noted that an $\bar{X}_{1-2}$ and an $\bar{X}_{2-3}$ is present to indicate that no target has been generated by the two-beam detection logic.

If the above existing conditions are provided to a W_2 an output will be enabled and applied to the threshold logic 16 to indicate that three adjacent beams meet the aforesaid requirements. The logic in the diagram for FIGURES 7B through 7E operate under the same conditions when adjacent E beams indicating a valid target.

In operation, the present invention sequentially and in a recirculating manner updates a plurality of radar beams which are in a stacked configuration. These conditions sampled by the threshold detection logic 16 and updated by the state of the new incoming beams for

each particular range bin time. The condition of these particular range bins are stored in the memory 17 after each sample is circulated for updating when the range bin next appears in the radar receiver 10. Once a valid target has been determined this data is also stored in the memory address location until the output of the previous mentioned probability tables indicate that the target has diminished. At this time, memory location will indicate that a target no longer exists in this particular range bin.

Having thus described one embodiment of this invention what is claimed is:

1. In a data processor:

memory means for continually storing updated data in a plurality of address locations;

data input means, said data input means including a plurality of input channels for receiving data from different sources simultaneously, and including a plurality of output channels for furnishing output data;

recirculating means coupled between said memory means and said output channels of said data input means and being responsive to the reception of the output data from said output channels of said data input means for updating the data stored in the data address locations of said memory means, said recirculating means including reversible counting logic circuitry coupled to said data input means and being responsive to the stored data in said memory means and to the output data from said data input means for changing the stored data in said memory means; and

detection means coupled to said data input means for indicating preselected data conditions of said data input means.

2. In the data processor as defined in claim 1 including: a read register coupled between said memory means and said recirculating means; and

a write register coupled between said recirculating means and said memory.

3. In the data processor as defined in claim 2 including: means, coupled to said memory means and said output channels, for detecting the preselected conditions of the data stored in adjacent locations and responsive to the data of adjacent input channels.

4. In a data processor:

memory means for continually storing updated data in a plurality of address locations;

data input means, said data input means including a plurality of input channels for receiving data from different sources simultaneously, and including a plurality of output channels for furnishing output data;

recirculating means coupled between said memory means and said output channels of said data input means and being responsive to the reception to the output data from said output channels of said data input means for updating the data stored in the data address locations of said memory means; and

detection means coupled to said data input means for indicating preselected data conditions of said data input means, said detection means further including a plurality of threshold gates being enabled by the preselected conditions determined by the contents of said stored memory in relation to the data received by said plurality of input channels.

5. A data processing system comprising:

reversible counting means;

logic means coupled to said reversible counting means for enabling said counting means to increase predetermined increments of a first value equal to N when data in a first state is received and to decrease predetermined increments of a second value equal to $N/2$ when data in a second state is received; and gating means coupled to said reversible counting means

15

and being enabled when the contents of said reversible counting means reaches a predetermined count.

6. A data processing system comprising:

reversible counting means;

logic means coupled to said reversible counting means for enabling said counting means to increase predetermined increments of a first value when data in a first state is received and to decrease a predetermined increment of a second value when data in a second state is received;

gating means coupled to said reversible counting means and being enabled when the contents of said reversible counting means reaches a predetermined count; and

a plurality of radar receivers coupled to said reversible counting means for receiving video returns, said radar receivers including means for digitizing said video returns and including a plurality of output means for distributing digitized video returns to said reversible counting means.

7. A data processing system as defined in claim 6 further comprising:

a memory device coupled to said logic means for storing video returns in a plurality of address locations corresponding to the respective ranges of each of the video returns.

8. A data processing system as defined in claim 6 further comprising:

a memory device coupled to said logic means for storing video returns in a plurality of address locations cor-

16

responding to the respective ranges of each of the video returns; and

a plurality of radar receivers coupled to said reversible counting means for receiving video returns, said radar receivers including means for digitizing said video returns and including a plurality of output means for distributing digitized video returns to said reversible counting means.

9. The data processing system as defined in claim 8 further including a write register coupled between said gating means and said memory device.

10. The data processing system as defined in claim 9 further including a plurality of detection logic circuits coupled to said memory device and said gating means.
